UNITED STATES PATENT OFFICE.

CLARENCE W. VOSS, OF ST. LOUIS, MISSOURI.

TOY.

1,317,184.

Specification of Letters Patent. Patented Sept. 30, 1919.

Application filed May 23, 1918. Serial No. 236,170.

To all whom it may concern:

Be it known that I, CLARENCE W. Voss, a citizen of the United States, and a resident of St. Louis, in the county of St. Louis and 5 State of Missouri, have invented certain new and useful Improvements in Toys, of which the following is a specification.

This invention relates to automatic toys, and more particularly to the type of automatic toys embodying a pivotally mounted movable member adapted to travel in a circular path by reason of a load supplied from a storage container and by reason of a counterweight which is carried at one end of the 15 pivoted movable member.

An object of this invention is to provide a toy of the nature specified which is simple in construction, durable and can be manufactured at a relatively small cost as well as a 20 toy which can be easily operated by a child.

More specifically, this invention comprehends the provision of a toy as specified which embodies an inclined storage trough or container, at the lower delivery end of 25 which the load receiving bucket rests when the toy is inactive, and to provide means operated upon being struck by a pin carried by the bucket during the movement thereof to release a load for the bucket and allow the 30 same to fall from the storage trough into the bucket which imparts a downward movement to the bucket, moving the movable member or arm, which carries the bucket, upon its pivot and depositing the load upon 35 the support of the toy. The momentum of the arm and the action of the counterweight thereon cause the arm to travel in a complete circuit and automatically operate the load release to permit the deposit of a subsequent load in the bucket, continuing the 40 operation of the arm until the supply of load in the storage trough is exhausted; and further to comprehend the provision of means for preventing the overloading of the bucket 45 and means to retain the load when deposited or emptied from the bucket.

Other objects of the invention will appear in the following detailed description, taken in connection with the accompanying drawing, forming a part of this specification, and in which drawing:

Figure 1 is a side elevation of the improved toy.

Fig. 2 is a top plan of the toy.

Fig. 3 is an enlarged fragmentary side ele-

vation of the toy illustrating a portion of the toy opposite to that which is illustrated in Fig. 1.

Fig. 4 is a section on the line 4—4 of Fig. 2.

Fig. 5 is a perspective view of the load receiving and carrying bucket.

Referring more particularly to the drawing, 1 designates the inclined storage trough or container for the loads that are delivered 60 or deposited into the load carrying bucket 2. The trough or container 1 is supported in its inclined position, by suitable upright supporting arms 3, the lower ends of which arms are attached to a base bar 4. The base 65 bar 4 is, constructed of a single length of relatively thin sheet metal and has the rear portion of its sides bowed outwardly as shown at 5 to form a relatively large confining face for the spherical loads indicated 75 at 6, which are delivered thereto by the bucket 2.

The load carrying bucket 2 is supported at one end of a pivotally mounted movable member 5 which is pivotally supported intermediate its ends upon a pin 6 carried by the upper ends of a substantially U-shaped standard 7. The lower ends of the U-shaped standard is attached to the forward free end 80 of the base bar 4.

The movable member 5 is constructed from a single piece of sheet metal, being cut and bent to form a pair of spaced arms 8 and 9, which have their intermediate portions connected to a saddle 10 which saddle is pivotally connected, by means of the pin 6' to the upstanding bracket 7. The outer ends of the arms 8 and 9 converge and have a counterweight 11 mounted thereon. The bucket 2 is formed integrally with the arms 8 and 9, 90 and extends from the inner ends of the arms, as clearly shown in the drawing. The rear-side 12 of the bucket 2 is preferably bent at an oblique angle to the bottom and sides of the bucket and it extends above the upper edge of the bucket to form a baffle or stop to prevent the spherical load 6 from bouncing out of the bucket during the operation of the toy. The lower edge of the front end or 100 side 13 of the bucket is bulged outwardly as shown at 14, to engage about a pin 15 which is attached to the lower inner corner of the bucket in any suitable manner and projects beyond the side of the bucket for engagement with a rocking arm 16. The arm 16 110

is formed integrally with the load arrester or stop structure 17 and this load arrester or stop structure 17 includes a substantially U-shaped bar 18, the bight portion 19 of which extends across the lower open end of the trough 1 forming an abutment or stop against which the lowermost spherical load 6 engages. In the initial operating of the toy, one of the loads 6, which may be ordinary marbles, is dropped into the bucket 2, which moves the bucket downwardly upon its pivot 6' imparting a rotary movement to the movable member 5. When the bucket 2 passes its lowermost point and starts upwardly, it will deposit the load or marble therefrom, which load or marble will pass between the parallel portions 5^a of the base member 4 and into the enlarged portion thereof where it will be confined until it is again placed within the storage trough. The momentum, and the action of the counterweight 11 will continue the movement of the movable member 5 after the marble or spherical load has been deposited or delivered by the bucket and when the bucket again reaches a receiving position, or rather immediately before it reaches a receiving position, as indicated in dotted lines in Fig. 1 of the drawing, the pin 15 will strike against the outer curved end 20 of the arm 16, and rock this arm upon its pivot 21, moving the stop 19 downwardly out of the path of the lowermost loads in the trough allowing this load to fall within the receiving bucket 2 which continues the movement of the movable member 5. The substantially U-shaped load arresting member 17 has an upstanding arm 22 formed thereon the upper end of which is bent inwardly over the trough and downwardly to form a load engaging portion 23. When the stop 17 is moved downwardly to permit the lowermost load in the trough to fall into the bucket, the downturned end 23 of the arm 22 engages the next to the last load in the trough, holding this and the remaining load against movement. An arm 24 is formed upon the member 17 and projects rearwardly from the pivot 21 thereof. A counterweight 25 is mounted upon the outer end of the arm 24 and immediately after the pin 15 passes off the end of the arm 16, the counterweight 25 will move the structure 17 upwardly, moving the bight portion 19 across the lower open or delivery end of the trough and at the same time move the downturned end 23 of the upstanding arm 22 out of engagement with the load, allowing these loads to move downwardly within the trough and position lowermost, against the stop 19 and in position for delivery to the bucket 2 upon its again reaching a receiving position.

The pin 21 is supported in any suitable manner, from the under surface of the storage trough or container 1.

The counter-balanced weight 11 is arranged, so that it would normally hold the movable member 5 in the position indicated by the dot and dash line a—a in Fig. 1 of the drawing, and out of a load receiving position. However when the last load has been delivered from the trough 1 into the bucket, and delivered from the bucket, the momentum of the movement of the arm will carry the arm or movable member about, causing it to pass and operate the arm 16. After the pin 15 has passed the arm 16 in this last movement, the momentum will soon be spent and the action of the counterweight will move the bucket upwardly, causing the pin 15 to engage beneath the arm 16, and hold the bucket in a load receiving position, so that when a person desires to again operate the toy, he may remove these spherical loads or marbles from the confining face within the supporting base 4, place all of them with the exception of one in the trough or container 1, and drop the remaining load into the bucket 2, which will start the operation of the toy, which operation will be automatically continued until all of the loads have been dispensed from the trough or container 1. Of course, it is not absolutely necessary to drop one of the loads into the bucket 2 to start the operation of the toy, as the movable member 5 may be moved about one circle, manually, to start the operation of the toy and to cause it to receive the first load from the trough or container.

Having thus fully described the invention, what is claimed is:

1. In a mechanical toy, the combination of a supporting base, an inclined load containing trough supported above said base, a movable member comprising a pair of spaced arms, enlargements formed upon a pair of corresponding ends of said arms and bent to form a load receiving bucket, means operated during movement of the movable member to successively deliver loads from the trough to the bucket.

2. In a mechanical toy, the combination of a supporting base, an inclined load containing trough supported above said base, a movable member pivotally mounted for movement in a circular path and comprising a pair of spaced arms, enlargements formed upon a pair of corresponding ends of said arms, and bent to form a load receiving bucket, the other ends of said arms converging, a counter-weight attached to said converging ends, and means operated during movement of the movable member to successively deliver loads from the trough to the bucket.

3. In a mechanical toy, the combination, of a movable member pivotally mounted for movement in a circular path and comprising an arm pivoted intermediate its ends, a load receiving bucket formed upon one end,

of said arm, a counter weight attached to the other end of said arm, a load container, means for arresting the delivery of loads to said bucket, a pin carried by said bucket 5 to operate said arresting means to permit a load to be delivered to the bucket when it reaches a receiving position, said pin adapted to engage beneath the load arresting means to hold the bucket in a receiving 10 position when the toy is inactive.

4. In a mechanical toy, the combination, of a movable member pivotally mounted for movement in a circular path and comprising an arm pivoted intermediate its ends, a load 15 receiving bucket formed upon one end of said arm, the rear wall of said bucket bent at an oblique angle to the bucket bottom and extended above the open edge of the bucket, a counter-weight carried by the 20 other end of said arm, a load container, means for arresting the delivery of loads to the bucket, means carried by the bucket to operate said arresting means to permit a load to be delivered to the bucket when it 25 reaches a receiving position, said bucket carrying means adapted to engage beneath said load arresting means to hold said bucket in a receiving position when the toy is inactive.

30 5. In a mechanical toy, the combination, of a movable member pivotally mounted for movement in a circular path and comprising an arm pivoted intermediate its ends, a load receiving bucket formed integrally 35 with said arm at one end thereof, a counter weight attached to the other end of the arm, a load container, means for arresting the delivery of loads to the bucket, means carried by said load arresting means to retain 40 subsequent loads against movement until said arresting means again assume a load arresting position, a pin carried by said bucket to operate said arresting means to permit a load to be delivered to the bucket 45 when it reaches a receiving position.

6. In a mechanical toy, a pivotally mounted movable member comprising a pair of spaced arms; enlargements formed upon a pair of corresponding ends of said arms and 50 bent to form a load receiving bucket.

7. In a mechanical toy, a pivotally mounted movable member comprising a pair of spaced arms, enlargements formed upon a pair of corresponding ends of said arms and bent to form a load receiving bucket, the rear wall of said bucket bent at an oblique angle to the bucket bottom and extending 55 above the open edge of the bucket.

8. In a mechanical toy, a pivotally mounted movable member comprising a pair of spaced arms, enlargements formed upon a pair of corresponding ends of said arms and bent to form a load receiving bucket, the rear wall of said bucket bent at an oblique 60 angle to the bucket bottom and extending 65

above the open edge of the bucket, the other ends of said arms converging, and a counter-weight attached to said converged ends.

9. In a mechanical toy, a load containing trough, means for arresting the delivery of 70 loads by said trough including a pivoted substantially U-shaped arm extending across the delivery end of the trough, an actuating arm formed upon said U-shaped arm, and a counterweight connected to the arm to return it to a load arresting position after operation, a pivotally mounted movable member comprising a pair of spaced arms, enlargements formed upon a pair of corresponding ends of said arms and bent to 75 reform a load receiving bucket adapted to receive a load from said trough.

10. In a mechanical toy, a load containing trough, means for arresting the delivery of 80 loads by said trough including a pivoted substantially U-shaped arm extending across the delivery end of the trough, an actuating arm formed upon said U-shaped arm a counterweight connected to the arm to return it to its load arresting position after operation, 85 an upstanding arm formed upon the U-shaped arm and having its upper end extended over said trough and downturned for engagement with subsequent loads during the delivery movement of the arresting 90 means to hold the subsequent loads against movement until the arresting means reaches a load arresting position after operation.

11. In a mechanical toy, the combination, of a supporting base, an inclined load containing trough supported above said base, a movable member, a load receiving and carrying bucket carried by said movable member, means for arresting the delivery of loads by said trough to said bucket including a substantially U-shaped arm extending across the delivery end of the trough, an actuating arm formed upon said U-shaped arm, a counterweight connected to the arm to return it to a load arresting position after operation, said supporting base having one end open to form a mouth to receive loads deposited from said buckets during movement of said movable member, an upstanding arm formed upon the U-shaped arm and having its upper end extended over said trough and downturned for engagement with subsequent loads during delivery movement of said arresting means to hold the subsequent loads against movement until the arresting means reaches a load arresting position after operation.

12. In a mechanical toy, the combination, of a movable member pivotally mounted for movement in a circular path, a load carrying bucket on one end of said movable member, a load container, means for arresting a delivery of loads from said container to said bucket including a substantially U-shaped arm extending across a delivery end 120 125 130

- of the trough, an actuating arm formed upon said U-shaped arm and adapted to be operated during movement of said load carrying bucket, a counterweight on the 5 arm to return it to a load arresting position after operation, means carried by said bucket for engagement with said operating arm, to permit a load to be delivered to the bucket when it reaches a receiving position, 10 and means carried by said U-shaped arm to retain subsequent loads against movement until said arresting means again assume a load arresting position.
13. In a mechanical toy, the combination, 15 of a movable member pivotally mounted for movement in a circular path and comprising a pair of spaced arms, enlargements formed upon corresponding ends of the arms and bent to form a load receiving bucket, the rear wall of said bucket bent at an oblique angle to the bucket bottom and extending above the open edge of the bucket, the opposite ends of said arms converging, a counterweight attached to said 20 converged ends, a load container, means for arresting the delivery of loads to said bucket, means carried by said bucket to operate said arresting means to permit a load to be delivered to the bucket when it reaches 25 a receiving position.
14. In a mechanical toy, the combination, 30 of a movable member pivotally mounted for movement in a circular path and comprising a pair of spaced arms, enlargements formed upon a pair of corresponding ends of the arms and bent to form a load receiving bucket, the rear wall of said bucket bent at an oblique angle to the bucket bottom and extending above the open edge of the 35 bucket, the opposite ends of said arms converging, a counterweight attached to said converged ends, a load container, means for arresting the delivery of loads to said bucket, means carried by said bucket to operate said 40 arresting means to permit a load to be delivered to the bucket when it reaches a receiving position, means carried by said load arresting means to retain subsequent loads against movement until said arresting means again assume the load stopping 45 position.
15. In a mechanical toy, the combination, 50 of a movable member pivotally mounted for movement in a circular path and comprising a pair of spaced arms, enlargements formed upon a pair of corresponding ends of the arms and bent to form a load receiving bucket, the rear wall of said bucket bent at an oblique angle to the bucket bottom and 55 extending above the open edge of the bucket, the opposite ends of said arms converging, a counterweight attached to said converged ends, a load container, means for arresting the delivery of loads to said bucket, means carried by said bucket to operate 60 said arresting means to permit a load to be delivered to the bucket when it reaches a receiving position, means carried by said load arresting means to retain subsequent loads against movement until said arresting means again assume the load stopping 65 position.
16. In a mechanical toy, the combination, 70 of a movable member, pivotally mounted for movement in a circular path, a load carrying bucket on one end of said movable member, a load container, means for arresting the delivery of loads to said bucket, from said container, means carried by the bucket to operate said arresting means to permit a load to be delivered to the bucket when it reaches 75 a receiving position, an upstanding arm formed upon said load arresting means and having its upper end extending over said load container and downturned for engagement with subsequent loads during delivery 80 movement of said arresting means to hold the subsequent loads against movement until the arresting means reaches a load arresting position after operation.
17. In a mechanical toy, the combination, 85 of a supporting base, a movable member pivotally mounted for movement in a circular path, and comprising a pair of spaced arms, enlargements formed upon a pair of corresponding ends of said arms and bent to 90 form a load receiving bucket, a load container, means for arresting the delivery of loads to said bucket from said container, means carried by said bucket to operate said 95 arresting means, to permit a load to be delivered to the bucket, when it reaches a receiving position, an upstanding arm formed upon said load arresting means and having its upper end extended over said load container and downturned for engagement with 100 subsequent loads during delivery movement of said arresting means, to hold the subsequent loads against movement until the arresting means reach a load arresting position after operation.
18. In a mechanical toy, a pivotally mounted movable member comprising a pair of spaced arms, enlargements formed upon a pair of corresponding ends of said arms and bent to form a load receiving bucket, the other ends of said arms converging, and a counterweight attached to said converged 105 ends.
19. In a mechanical toy, the combination, 110 of a supporting base, an inclined load containing trough supported above said base, a movable member pivotally mounted for movement in a circular path and comprising an arm pivoted intermediate its ends, a load receiving bucket formed upon one end 115 of said arm, a counterweight attached to the other end of said arm and adapted to bring said bucket into a load-receiving position upon the emptying of a load therefrom, means for arresting the delivery of loads to 120
- 125
- 130

said bucket, pins carried by said bucket to operate said arresting means to permit the load to be delivered to the bucket when it reaches a receiving position, said pin adapted to engage beneath the load arresting means to hold said bucket in a receiving position when the toy is inactive.

20. In a mechanical toy, the combination, of a supporting base, an inclined load containing trough supported above said base, a

movable member comprising a pair of spaced arms, enlargements formed upon a pair of corresponding ends of said arms and bent to form a load receiving bucket, a pin extending transversely from the lower forward corner of said bucket, and means operated by said pin during movement of said arm to successively deliver loads from the trough to the bucket. 15
